UNITED STATES PATENT OFFICE.

JACOB R. MOORE, OF CLAYTON, MICHIGAN, ASSIGNOR OF ONE-HALF TO
HENRY BOVEE, OF SAME PLACE.

COMBINED HEATING APPARATUS AND DRYING-RACK.

SPECIFICATION forming part of Letters Patent No. 295,663, dated March 25, 1884.

Application filed June 27, 1883. (No model.)

to all whom it may concern:

Be it known that I, JACOB R. MOORE, a citizen of the United States, residing at Clayton, in the county of Lenawee and State of Michigan, have invented certain new and useful Improvements in Combined Heating Apparatus and Drying-Rack; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has for its object to provide a novel and simplified heating apparatus and drying-rack combined which is adapted for operation in connection with an ordinary stove; and it consists, essentially, of a supporting frame or clamp provided with two adjustable crank-rods, which are provided, respectively, with the heating device and drying-tray, the former being so arranged as to be readily introduced into the fire-chamber of the stove 20 or removed therefrom at pleasure, while the drying tray or frame swings freely over the upper part of the stove at any desired height. It further consists of other details of construction and general arrangement of parts, all as 25 30 will be hereinafter more fully described, and specifically designated in the claims.

In the accompanying drawings, Figure 1 represents a front elevation of my complete invention; Fig. 2, a detail side view of the supporting-frame; Fig. 3, a detail plan view of the device for adjusting the heating apparatus or drying-tray at suitable heights; and Figs. 4 and 5 are detail sectional views.

Similar letters of reference occurring on the 40 several figures indicate like parts.

In carrying out my invention the supporting-frame A is provided with the usual clamping-jaws and set-screws for attaching the same to the hearth or flange of the stove, the front 45 portion of said frame terminating in a vertical upright, A', which is provided upon each upper and lower end with a plate, B, secured thereto by the nuts a, the said plate B having two circular openings, b b', of unequal diameters, through the same near its central portion, and a wedge-shaped holding device, c, to

one side thereof, as fully shown in the drawings.

C represents a hollow vertical tube or pipe, which is loosely adjusted in the larger circular openings b of the upper and lower plates, B, and held therein at suitable heights by means of the chain d, one end of which is secured to a projection upon the lower part of said tube or pipe, while the upper portion is 55 adapted to be drawn into the wedge-shaped recess of the holding device c, and the free end of the chain provided with a ring, d', as fully shown in Figs. 1 and 2.

D represents a rod bent into the form of a 65 crank, the longer end e of which projects down into the open upper end of the tube or pipe C, while the short and upwardly-projecting end e' is adapted to receive the drying frame or tray E, which is composed of two parallel pipes 70 or tubes, f, united at their centers by a cross rod or tube, g, having an open thimble or joint, g', at its center to fit over upon the end e' of the crank-rod D, as fully shown in Fig. 4.

F represents a rod similar in shape to that 75 of the crank-rod D, the longer and downwardly-projecting end h of which fits in the smaller circular openings b' in the plates B, and adjusted therein at suitable heights by the chain i engaging with the same, in a manner similar to 80 that already described upon the tube or pipe C, the shortest and upwardly-projecting end h' of the said rod F being adapted to receive one end of the heating device, as shown in Fig. 1. This heating device or apparatus is com- 85

posed of an upper pipe, k, which opens into a hollow head-block, m, at one end, and is provided with a gasoline or other suitable supply-tank, G, at the opposite end, and directly over the point where the apparatus is pivoted upon 90 the end h' of the rod F, a suitable stop-cock, l, being provided at or near the outer end of said pipe, to regulate the flow of gasoline from the tank to the burners. Directly beneath the upper pipe, k, and projecting from the head-block m, is provided a short pipe, n, which is closed at its outer end, and adapted to receive burners of any desired or suitable kind. Two screw-plugs, o, are provided upon the end of the head-block m, on a line with the pipes k 95 and n, so as to permit of the easy cleaning of the said pipes at any time.

The construction of my invention being as described, it will be observed that in the operation of the same the supporting-frame A is clamped to the flange or hearth of an ordinary stove, and the several parts of the apparatus being adjusted in the position already described, the heating device can be readily swung around into the fire-chamber through the usual door upon the side or front, and the 5 drying frame or tray revolved around upon the stove directly over the heat. A suitable draft-plate may be provided at the open door of the stove, to regulate the heat from the burners, and to conduct the products of combustion up the usual flue.

By means of my improvements fruits of all kinds may be readily evaporated or dried in the best manner, and also the ordinary methods of kindling a fire in the stove may be dispensed 10 with and my apparatus substituted in place thereof, requiring but a few minutes' time for the adjustment of the same in place, and securing sufficient heat for the ordinary purposes of cooking, the scent of the oil or gasoline being conducted up the usual flue, thereby obviating the smell usually attendant upon the 15 employment of all other devices used for such purposes.

Having thus described my invention, what I claim as new and useful is—

1. The herein-described heating device and drying-tray combined, consisting of the supporting-frame A, provided with the plates B, having chain-holding devices c and circular openings b b', adapted to receive the tube C, crank-rods D and F, which are adjustably secured therein by the chains d and i, and carrying the drying-frame E, and the frame of the oil or gasoline burners, all substantially as and for the purpose specified.

2. The supporting-frame A, provided with the upright A', adapted to receive the plates B, having the chain-holding devices c and circular openings b b', in combination with the tube C, crank-rods D and F, chains d and i, 45 and the drying-frame E, and heating device, all substantially as and for the purpose specified.

In testimony whereof I affix my signature in presence of two witnesses.

JACOB R. MOORE.
